METHOD OF AND APPARATUS FOR FLAME MACHINING

Everett P. Jones, Elizabeth, N. J., assignor to The Linde Air Products Company, a corporation of Ohio

Application April 3, 1940, Serial No. 327,587

8 Claims. (Cl. 148—9)

This invention relates to a method of and apparatus for flame machining in which metal is thermochemically removed from the surface of a metallic body by applying an oxidizing gas stream obliquely against and progressively along successive portions of such surface which is at an ignition or kindling temperature to form a groove therein and relates more particularly to a method of and apparatus for controlling the flow of molten slag from such a flame machined groove.

In many instances it is desirable to remove metal from only a portion of a metallic surface to produce a cut which slopes inward from an uncut portion of the surface and extends to an extreme edge of the metallic body. This is particularly true when it is desired to produce cuts at the edges of plates or other structural shapes which are subsequently united by welding. Such cuts or bevels may take the shape of a J so that, when two plates having such cuts are arranged with the beveled edges adjacent to each other, a U-shaped groove is provided therebetween that is suitable for welding. It has been customary to form such J-grooves by thermochemically forming a U-groove between abutting edges of separate plates thereby forming a J-groove in the edge of each plate. In many instances this is impracticable or impossible.

Ordinarily when attempting to thermochemically form a J-groove in the surface of a ferrous metal body by means of an oxidizing gas stream, the molten slag, which usually comprises both oxidized and fused or molten metal, is forced out of the groove and over the edge or edges of the groove and over the surface ahead of and to the side of the cut or groove. Especially when forming a J-groove in a substantially vertical surface such as the vertical edge surface of a steel plate, the molten slag flows down over the lower edge of the plate or flows over the uncut portion of the surface to form adhering fins which must be removed, and in addition, flows over the surface ahead of the cut. Due to the action of gravity and the deflection of the gas stream molten slag does not flow uniformly over the surface ahead of the cut and non-uniformly preheats the surface metal thereby causing the oxidizing gas stream to remove a non-uniform layer of metal from successive surface portions and causes the J-groove to be of a non-uniform depth. Formerly, it has been found to be very difficult if not impossible to thermochemically form a satisfactory J-groove that is uniform and free of fins in only one plate edge.

Accordingly, it is an object of this invention

to provide an improved method of flame machining in which metal is thermochemically removed from the surface of a metal body to produce a J-groove therein; to provide such a method of flame machining wherein the direction of flow of the slag is controlled; to provide such a method of flame machining for thermochemically forming a J-groove in the surface of a metal body that is free of fins and is of a uniform contour; to provide such a method of flame machining a J-groove in the surface of a metal body that is suitable for abutting against a similarly-grooved body for welding the bodies together; and to provide apparatus for performing such methods of flame machining.

These and other objects and novel features will be apparent from the accompanying drawing in which:

Fig. 1 is a schematic view of one form of apparatus embodying the features of the present invention;

Fig. 2 is an enlarged isometric view of a portion of the apparatus of Fig. 1;

Fig. 3 is a sectional view taken along line 3—3 of Fig. 2;

Fig. 4 is a partial sectional view of a plate having a J-groove formed in a surface thereof; according to the present invention; and

Fig. 5 is a view similar to Fig. 4 disclosing a modified J-groove.

To remove surface metal by flame machining, the metal must be heated to the ignition or kindling temperature before the oxidizing gas stream is progressively applied thereto. The entire steel body may be heated to the ignition temperature as in a furnace or an electric arc or high temperature heating flame may be utilized to heat successive portions of the surface metal to be removed to the ignition temperature prior to the application of the oxidizing gas stream. According to this invention a single nozzle N is employed to provide an oxidizing gas stream and a plurality of high temperature heating flames. The blowpipe nozzle N may have a central passage 10 for oxidizing gas, such as oxygen, to provide an oxidizing gas stream of suitable character. A plurality of preheating passages 11 surrounding or partially surrounding the central passage 10, are provided and supplied with a combustible gas mixture such as oxygen and acetylene to produce preheating flames to heat the surface metal to the ignition or kindling temperature. Though any nozzle of the character which is suitable for flame machining may be used, a nozzle which has been found to be especially suitable

for carrying out this invention as herein described, is disclosed in my copending United States Patent application, Serial No. 254,205, filed February 2, 1939.

The blowpipe nozzle N may be supported and moved relatively to the plate 12 by any suitable means. It is preferable that a self-propelled carriage 13 be used for supporting and moving the blowpipe 14 to produce more accurate cuts or grooves. Such a carriage 13 may be supported on the upper surface of the plate 12 and guided by a rail mounted thereon or may be supported by other means such as separate rails, or other suitable supporting means, on a table extending over or adjacent to the plate 12. The blowpipe 14 and the operatively attached blowpipe nozzle N may be adjustably secured in a bracket 15 supported by a vertically and transversely adjustable overhanging arm 16 mounted on the carriage 13. A suitable carriage apparatus of such character is described and claimed in the United States Patent No. 2,183,605 to J. H. Bucknam and A. J. Miller, December 19, 1939.

In order to remove surface metal according to the present invention, the nozzle N is positioned at the edge surface 19 of the substantially horizontal plate 12 so that the preheating flames and the oxidizing gas stream discharged from the outlet orifices of passages 10 and 11 of the nozzle N are directed against the surface metal to be removed, substantially in the direction of the successive portions of metal to be removed.

The combustible gas issuing from the passages 11 heats the metal directly ahead of the nozzle to the ignition temperature and the oxidizing gas issuing from the passage 10 impinges on this heated surface metal and causes the same to ignite and burn. When the oxidizing gas stream impinges on the surface of the metal to be removed, the stream produces the inwardly curved portion 20 of the J-groove. The oxidizing gas stream is deflected upwardly and sweeps over the upper portion of the heated surface to the extreme upper edge of the plate to produce a substantially straight portion 21 of the groove. This burning or oxidation of the metal takes place progressively as each successive portion of metal is exposed to the oxidizing gas stream. When producing a groove in this manner at the edge of the plate 12, the surface metal is removed in the form of molten slag, as indicated generally at S, in such a manner that the newly exposed surface is in the shape of a J-groove. When the plate 12 is positioned against or adjacent to a similarly flame machined plate, the two J-grooves when aligned form a U-groove, particularly suitable for the welding together of the two plates.

A conduit 22 is connected through a valve 23 to a suitable source of gas under pressure, such as air, and may be attached to the blowpipe or mounted on the blowpipe supporting means in order to be moved along the cut simultaneously with the blowpipe nozzle. The conduit is preferably supported in an adjustably fixed, predetermined relation relative to the nozzle. A branch portion 24 of the tube 22 is provided and positioned to direct a stream of air upwardly and inwardly against the vertical surface 19 of the plate 12 substantially adjacent and along the forward edge of the cut, as shown at 27, to force all of the molten slag up onto the top of the plate thereby preventing the molten slag from flowing down over the uncut surface portion 28 and preventing the molten slag from

flowing ahead of the groove over the uncut portions of surface 19. The extended portion 29 of tube 22 contains a plurality of drillings 30 to project a plurality of air jets upwardly and obliquely against the vertical surface 19 of the plate as an aid in preventing the molten slag from flowing from the groove and over the surface ahead of the cut, but primarily to prevent the molten slag which has been forced upwardly onto the upper surface of the plate from flowing from the upper surface over the vertical surface 19. The air jet from tube 24 flows upwardly across and to the far edge of surface 19 and forces the slag upwardly onto the upper surface of the plate and the jets from the tube 29 primarily prevent the slag from flowing over the upper edge and down across the vertical surface. The single jet from tube 24 is ordinarily sufficient under some conditions for controlling the flow of the molten slag, but usually better results will be obtained by using a plurality of air jets as described.

Although the removed surface metal can be reduced completely to an oxidized form, considerable economy can be effected by removing a substantial portion of the surface metal without completely oxidizing it so that the molten slag contains molten metal. If the molten slag flowed down over the uncut surface portion 28, the slag would form fins on the surface 28 and along the edges of such surface. These fins are usually difficult to remove and must be removed before the welding operation. The molten slag which flows up onto the upper cold surface of the metal body does not adhere to the metal and usually may be brushed off with little effort. The molten slag is at a high temperature and if allowed to flow out of the groove and over the uncut surface 19 in front of the groove, the surface metal will be non-uniformly preheated and the depth of the J-groove will not be uniform as the desurfacing reaction proceeds more vigorously where the metal is hotter. By the present invention, the air jets control the flow of molten slag from the groove to prevent the slag from flowing over the uncut surface portions 19 or 28 so that no fins are formed and there is no undesirable non-uniform preheating of the surface metal whereby a uniform J-groove is formed that is free of fins.

The present method of flame machining is particularly successful in preparing edges of relatively thick metal plates for welding. The flame machined surface carries a very thin coating of iron oxide and the thickness of this iron oxide film is substantially equal to a wave length of light. Beneath such oxide film there is a thin layer of metal containing carbon in an amount greater than that of the original metal before the flame machining operation. In this manner, a flame machined surface is so conditioned and improved that subsequent welding of two plates having such surface is considerably facilitated and the resulting welded joint has a strength and uniformity superior to welded plates heretofore beveled by mechanical means. While the nozzle N is herein shown as being so positioned as to direct the oxygen stream inwardly and slightly downwardly against the surface, the nozzle N could be so positioned as to be directed inwardly and slightly upwardly depending upon the contour of the groove desired.

As herein shown and described metal is thermochemically removed along a corner or edge portion of the metal body and the air jet or jets

are directed against and blow across to the far edge of that surface which is to be disposed adjacent or against a similarly grooved edge for welding. It is not necessary that the uncut surface portion 28 be as shown and described but the lower edge of the cut could coincide with the bottom edge of the plate so that the uncut surface portion would be of infinitesimal width, as at 32 of Fig. 5. In addition, it is not necessary that the surface being flame machined be vertical but the surface can be sloping or horizontal and the gas jets employed for controlling the flow of the molten slag could be of a different number or size depending upon the form of the groove and the amount of slag.

The shape of the groove is dependent upon the velocity of the oxidizing gas stream and its rate of movement with respect to the surface of the metallic body and the particular angle at which the gas stream is applied against the surface. Generally the velocity of the gas stream and its rate of movement are selected to obtain the maximum gas economy. By varying the angle at which the gas stream is applied, grooves having a different predetermined sectional contour can be formed.

This invention is not confined to forming grooves in straight surfaces but may be utilized for forming grooves in a curved surface such as the edge surface of a circular plate. The tubes 22, 24, and 29 may be bent or curved so that the jets from tubes 24 and 29 are directed against the correct portions of the surface to prevent the slag from flowing over the bottom edge of the surface or flowing over the surface ahead of the cut.

It will be readily apparent to those skilled in the art that various modifications and substitutions can be made in the embodiment of the invention herein disclosed without departing from the scope or spirit of the invention.

What is claimed is:

1. A method of flame machining in which metal is thermochemically removed along the corner portion formed by two contiguous surfaces of a metallic body to produce a J-groove therein, which comprises heating at least a portion of such metal to the temperature at which it will ignite when an oxidizing gas stream is applied thereon; directing an oxidizing gas stream against the metal to be removed and substantially in the direction of the successive portions of metal to be removed; applying against one of said surfaces at a position, approximately adjacent an advancing forward edge of said groove, at least one gas stream which flows across said surface ahead of said groove to prevent molten slag from flowing over the uncut portion of said surface; and moving both said oxidizing gas stream and said slag directing stream relatively along successive portions of said corner.

2. A method of progressively forming a J-groove in a ferrous metal body by thermochemically removing metal along a corner portion formed by two contiguous surfaces thereof, which comprises heating at least a portion of the metal to be removed to the ignition temperature; applying a stream of oxygen against the metal to be removed to thermochemically react with such metal, such stream being applied in the direction of the successive portions of metal to be removed; applying against and across a portion of one of said surfaces of said body and substantially ahead of the advancing forward boundary of said groove a stream of air directed to pre-

vent the slag from flowing out of said groove onto any portion of said last mentioned surface ahead of said groove; and progressively moving both said oxygen stream and said air stream relatively along said corner portion.

3. A method of flame machining in which metal at an ignition temperature is thermochemically removed from the vertical surface of a metallic body to produce a J-groove therein, which comprises applying against such metal an oxidizing gas stream directed substantially toward the successive portions of metal to be removed; directing a stream of gas upwardly against said surface to direct the flow of molten slag from said groove in an upward direction; and moving both said oxidizing gas stream and said slag directing stream relatively along successive portions of said surface.

4. A method of flame machining in which metal at an ignition temperature is thermochemically removed from the vertical surface of a metallic body to produce a J-groove therein adjacent a lower uncut portion of said surface, which comprises applying an oxidizing gas stream against the metal to be removed and substantially in the direction of the successive portions of metal to be removed; applying against said surface a stream of gas inclined at an acute angle transversely of said surface and directed upwardly away from said uncut surface portion to the far edge of said surface to direct the flow of molten slag upwardly from said groove onto the upper surface of said metallic body; and progressively moving all of said gas streams relatively along successive portions of said surface to progressively form said groove.

5. A method of flame machining in which metal at an ignition temperature is thermochemically removed from an edge portion of a metallic body to produce a groove therein adjacent a lower uncut portion of a vertical surface of said body, which comprises applying an oxidizing gas stream against the metal to be removed and directed toward successive portions of metal to be removed; applying against said surface a stream of gas inclined at an acute angle transversely of said surface and directed upwardly away from said uncut surface portion to direct the flow of molten slag upwardly from said groove onto the upper surface of said metallic body; applying at least one additional stream of gas upwardly against said surface to prevent said molten slag from flowing from said upper surface down over said vertical surface; and progressively moving all of said gas streams relatively along successive portions of said surface.

6. A flame machining apparatus for thermochemically removing metal from along a corner formed by contiguous surfaces of a metallic body to form a J-groove therein, comprising nozzle means for applying an oxidizing gas stream against and along the metal of said corner to be removed; means for applying a gas stream against and across one of said surfaces of said body and substantially adjacent and along a forward advancing border of said J-groove; and mechanism for supporting said nozzle means and said other gas applying means in such predetermined relative relationship and for progressively moving said nozzle and said other gas applying means lengthwise along successive portions of said corner.

7. A flame machining apparatus for thermochemically removing surface metal from an upper portion of a vertical side surface of a metallic

body to form a J-groove therein adjacent an uncut lower portion of said vertical surface comprising nozzle means for applying an oxidizing gas stream against the metal to be removed substantially in the direction of the portions from which metal is to be removed; means for applying a gas stream upwardly against and across said vertical surface ahead of said groove to cause the slag from said groove to flow upwardly and onto the upper surface of said body; means for applying at least one additional gas stream against and across said vertical surface primarily for preventing said slag from flowing from said upper surface over said vertical surface; and means for supporting and moving all of said nozzle and said gas applying means along successive portions of said vertical surface.

8. A flame machining apparatus for thermo-chemically forming a J-groove in the surface of a steel body which comprises nozzle means for 20

directing at least one preheating jet against the metal to be removed and for directing an oxidizing gas stream against such metal, said jet and said stream being directed substantially lengthwise of said surface in the direction of the successive portions from which metal is to be removed; means for applying a gas stream, such as an air stream, against and across said surface approximately adjacent the forward edge of said groove to prevent the slag from flowing from said groove onto the uncut surface portion of said surface; and self-propelled carriage means for adjustably supporting said nozzle means and said other gas applying means in predetermined relationship relative to each other and to said surface and for progressively moving said nozzle means and said other gas applying means along successive portions of said surface whereby said groove is progressively formed in said body.

EVERETT P. JONES.
